DESIGN FOR A COMBINED REFRIGERATOR DISPENSING AND STORAGE CABINET

Richard H. Heise, St. Louis, Mo., assignor to S. G.
Adams Company, St. Louis, Mo., a corporation
of Missouri

Application August 22, 1936, Serial No. 64,529

Term of patent 3½ years

To all whom it may concern:

Be it known that I, Richard H. Heise, a citizen of the United States of America, residing in the city of St. Louis and State of Missouri, have invented a new, original, and ornamental Design for a Combined Refrigerator Dispensing and Storage Cabinet, of which the following is a specification, reference being had to the accompanying drawing forming a part thereof.

Fig. 1 is a perspective view of a combined re-

frigerator dispensing and storage cabinet showing my new design.

Fig. 2 is a perspective view of a combined refrigerator dispensing and storage cabinet showing my new design, taken from the end opposite to that shown in Fig. 1.

I claim:

The ornamental design for a combined refrigerator dispensing and storage cabinet, as shown.

RICHARD H. HEISE.
